BRUSH AND COMB CLEANER

James H. Stamp, Borough of Middlesex, N. J., assignor to Tek Hughes, Inc., a corporation of New York

Application October 15, 1948, Serial No. 149,128

Term of patent 14 years

(Cl. D86—10)

To all whom it may concern:

Be it known that I, James H. Stamp, a citizen of the United States, residing at Borough of Middlesex, in the county of Middlesex and State of New Jersey, have invented a new, original, and ornamental Design for a Brush and Comb Cleaner, of which the following is a specification, reference being had to the accompanying drawing, forming a part thereof in which

Fig. 1 is a plan view of a brush and comb cleaner, embodying my new design;

Fig. 2 is a side elevation as viewed from the top of Fig. 1;

Fig. 3 is an end elevation as viewed from the left of Fig. 2; and

Fig. 4 is a section on the line 4—4 of Fig. 1.

I claim:

The ornamental design for a brush and comb cleaner, substantially as shown.

JAMES H. STAMP.
